UNITED STATES PATENT OFFICE.

JOHN E. MARSDEN, OF SEDGWICK, PENNSYLVANIA.

DESIGN FOR AN ARTICLE OF MANUFACTURE.

46,259.

Specification for Design.

Patented Aug. 11, 1914.

Application filed April 7, 1914. Serial No. 830,301. Term of patent 7 years.

To all whom it may concern:

Be it known that I, JOHN E. MARSDEN, a citizen of the United States, and a resident of Sedgwick, in the county of Philadelphia and State of Pennsylvania, have invented a new, original, and ornamental Design for an Article of Manufacture, of which the following is a specification, reference being had to the accompanying drawing, forming part thereof.

The figure is a face view of my new design to be applied to an article of manufacture.

I claim:

The ornamental design for an article of manufacture, as shown.

JOHN E. MARSDEN.

Witnesses:

L. E. HALL,
G. A. CLARKSON.
